United States Patent Office

Des. 180,955
Patented Sept. 10, 1957

180,955

PHONOGRAPH RECORD HOLDER

John L. Lyons, Glendale, Calif.

Application August 17, 1955, Serial No. 37,530

Term of patent 14 years

(Cl. D33—3)

The figure is a perspective view of a phonograph record holder embodying my new design.

I claim:

The ornamental design for a phonograph record holder, as shown.
